VELOCIPEDE

Carl W. Hedstrom, Gardner, Mass., and John Cuccio, Westport, Conn., assignors to Hedstrom Union Company, Fitchburg, Mass., a corporation of Massachusetts

Filed May 9, 1961, Ser. No. 65,081

Term of patent 7 years

(Cl. D34—15)

F I G. 1

F I G. 2

FIG. 3

FIG. 4

FIG. 1 is a side view in perspective of a velocipede embodying our new design;

FIG. 2 is a rear view in perspective thereof;

FIG. 3 is a front view thereof; and

FIG. 4 is a top view thereof.

The dominant features of our design reside in the portions shown in full lines.

We claim:

The ornamental design for a velocipede, substantially as shown and described.
